UNITED STATES PATENT OFFICE

HENRY K. PALMER, OF LOS ANGELES, CALIFORNIA

SIGN FRAME

Application filed October 7, 1930. Serial No. 486,973.

This invention relates to frames, and more particularly to a frame for illuminated street signs.

The general object of the invention is to provide a novel frame for illuminated street signs, by means of which the units of the sign may be readily assembled about a street lamp post and mounted thereon or detached and removed from the post if desired.

Other objects and advantages will appear hereinafter.

The invention is illustrated in the annexed drawings which form a part of this specification and in which,

Fig. 1 is a plan view of my invention shown assembled about and mounted upon a street lamp post for use as an illuminated street sign, the sign plate, reflector and top plate of the sign being omitted.

Fig. 2 is a transverse vertical section of my invention taken on a line 2—2 of Fig. 1 with the lamp post omitted.

Fig. 3 is a transverse vertical section of one unit of my sign frame taken on line 3—3 of Fig. 1.

Fig. 4 is a front view of one of the corners of my sign frame as viewed from line 4—4 of Fig. 1.

Fig. 5 is a side view of one of the end members of one of the male frame units as viewed in the direction of arrows 5 in Fig. 1.

Fig. 6 is a side view of one of the end members of one of the female frame units as viewed in the direction of the arrows 6 in Fig. 1.

Fig. 7 is a bottom view of two assembled end members of a pair of male and female frame units as viewed from the lines 7—7 of Figs. 5 and 6.

Fig. 8 is a front elevation of a street sign embodying my invention.

Fig. 9 is a rear elevation of a sign unit including a male frame unit of my invention.

Fig. 10 is a rear elevation of a sign unit including a female frame unit of my invention.

Fig. 11 is a fragmentary front view of one of my frame units.

Fig. 12 is a cross section of my sign frame taken on line 12—12 of Fig. 1.

Fig. 13 is a fragmentary horizontal section taken on line 13—13 of Fig. 4.

Corresponding parts are designated by the same reference characters in all the figures.

My sign frame is composed of male units 1 and female units 2 for the sign units 3 and 4 respectively.

Each male unit 1 comprises a pair of triangular end members 5 and three edge strips 6, 7 and 8. Each female unit 2 comprises a pair of triangular end members 9 and three edge strips 6, 7 and 8.

Each end member 5 and 9 is formed with a front rail 10, a rear rail 11 and a top rail 12, against which rails abut the ends of the sign plate 13, the reflector 14 and the top plate 15 respectively of a sign unit 3 or 4. Each front rail 10 is formed with an internal flange 16 along its outer edge upon which flange rests a sign plate 13 at one end. Each rear rail 11 is formed with an internal flange 17 along its rear edge upon which flange rests a reflector 14 at one end. The top rail 12 of each end member is formed with lugs 18 along its lower edge and with an internal flange 19 along its upper edge, between which lugs and flange of each end member is fitted a end of a top glass 15, which glass is supported by said lugs. The top rail 12 of the end member 5 of each male frame unit 1 is formed with an external flange 20 along its upper edge which overlap the outer edge of the top rails 12 of the end members 9 of the adjoining female frame members 2, forming a weather joint between said end members 5 and 9 as shown in Fig. 12. On the outer edge of the front rails 10 of the end members 9 of the female frame units 2 are formed bosses 21 provided with screw holes 22 to receive screws 23 for holding corner pieces 24 over the outer rails 10 of the end frame members 5 and 9 of adjoining frame units 1 and 2, providing weather joints between said adjoining rails 10 as shown in Figs. 1, 3, 4, 8 and 11. On the outer side of the rear rails 11 of the end members 5 of the male frame units 1, are formed depending threaded shanks 25 and shoulders 26 at the base or up-

per end of said shanks, which shanks are extended through bores 27 in bosses 28 formed on the outer side of the inner rails 11 of the end members 9 of the female units 2, the shoulders 26 of the end members 1 resting upon the upper end of said bosses 28, whereby the male frame units 1 are mounted upon the female frame units 2, and the sign units 3 and 4 assembled at right angles to each other with their adjoining ends mitred together by the end frame members 5 and 9 which extend at an angle of forty-five degrees to their edge strips 6, 7 and 8. (See Fig. 1.) The bosses 28 of the frame end members 9 are fitted in sleeves 29 on the outer ends of the arms 30 of a bracket 31 secured on a lamp post 32, the bosses 28 being formed with external flanges 33 at their upper ends which flanges rest upon the upper ends of said sleeves 29, whereby the sign is mounted upon said lamp post. Nuts 34 screw on the lower ends of the shanks 25 against the lower ends of the bosses 28, whereby the male frame units 1 are detachably secured to the female frame units 2 and the sign detachably mounted on the bracket 31 and the lamp post 32.

The edge strip 6 of each frame unit 1 or 2 is V-shaped in cross section and is secured at its ends to the flanges 17 in the lower corners 30 of the end members 5 or 9 of said frame units by screws 35. The edge strip 7 of each frame unit 1 or 2 is V-shaped in cross section and is secured at its ends to the flanges 17, in the rear upper corners of the end members 5 or 9 of said frame units, by screws 36. Each front edge rail 8 is formed with up-turned flanges 37 at its ends, and screws 38 are driven through said flanges into the upper front corners of the end frames 5 or 9 of the frame units 1 or 2.

The lower edges of each sign plate 13 and reflector 14 rest and are supported in the lower edge strip 6 of a frame unit 1 or 2. The upper edge of each sign plate 13 and the forward edge of each top plate 15 rest within the upper front edge strip 8 of each reflector 14 and the rear edge of each top plate 15 rest within the rear upper edge strip 7 of a frame unit 1 or 2.

50. The end frame members 5 and 9 being formed by the rails 10, 11 and 12 leaves openings 40 and 41 within said end members which openings permit light from one sign unit 3 or 4 to enter the adjoining sign units, whereby the reflection of shadows from the end members of a sign unit 3 or 4 through the glass sign plate 13 of the sign unit is prevented.

I claim as my invention:

60. 1. A sign composed of a plurality of sign units, each sign unit including a frame unit, each frame unit including end frame members, each end frame member being formed by side rails leaving an opening within said rails, the end members of each frame unit

being fitted to the end members of adjoining frame units and means for securing said frame units together, external flanges along the upper rails of certain of said end frame members, which flanges overlap the upper rails of the adjoining end frame members.

2. A sign composed of a plurality of sign units, each sign unit including a frame unit, the frame unit of each sign unit being mitred at its ends with the ends of the frame units of adjoining sign units, apertured bosses formed on the ends of certain of said frame units, shanks formed on the ends of the other frame units to be extended through said apertured bosses, and shoulders at the bases of said shanks adapted to rest upon the upper ends of said bosses.

3. A sign composed of a plurality of sign units, each sign unit including a frame unit, each frame unit including end frame members, fitted to the end members of adjoining frame units, apertured bosses on the end members of certain of said frame units, shanks formed on the end members of the other frame units adapted to project through said apertured bosses, and shoulders at the bases of said shanks for engaging the upper ends of said bosses.

4. A sign composed of a plurality of sign units, each sign unit including a frame unit, the frame unit of each sign unit being joined at its ends with the ends of the frame units of adjoining sign units, apertured bosses formed on the ends at the inner corners of certain of said frame units, shanks formed on the ends at the inner corners of the other frame units to be extended through said apertured bosses, shoulders at the bases of said shanks adapted to rest upon the upper ends of said bosses, corner pieces covering the joints between the ends of said adjoining frame units at the outer corners thereof, and means for detachably securing said corner pieces to the ends of said frame units.

HENRY K. PALMER.
